(57) **CLAIM**

The ornamental design for an emergency power flashlight, as shown and described.

DESCRIPTION

FIG. 1 is a perspective view of the emergency power flashlight showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated with numeric 9 in FIG. 1.

The portions of the emergency power flashlight shown in dashed broken lines forms no part of the claimed design. The dot-dash broken lines framing portions of the claimed design are included for the purpose of illustrating enlargements, and form no part of the claimed design.
